[57] CLAIM

The ornamental design for a class ring, as shown and described.

DESCRIPTION

FIG. 1 is a perspective view of a class ring showing my new design;

FIG. 2 is a top plan view of the class ring of FIG. 1; FIG. 3 is a bottom plan view of the class ring of FIG. 1; FIG. 4 is a right side elevational view of the class ring of FIG. 1;

FIG. 5 is a left side elevational view of the class ring of FIG. 1;

FIG. 6 is a front elevational view of the class ring of FIG. 1;

FIG. 7 is a back elevational view of the class ring of FIG. 1;

FIG. 8 is a perspective view of a class ring showing a second embodiment of my new design;

FIG. 9 is a top plan view of the class ring of FIG. 8;

FIG. 10 is a bottom plan view of the class ring of FIG. 8;

FIG. 11 is a right side elevational view of the class ring of FIG. 8; a left side elevational view would be a mirror image of FIG. 11;

FIG. 12 is a front elevational view of the ring of FIG. 8; a back elevational view would be a mirror image of the drawing shown in FIG. 12;

FIG. 13 is a perspective view of a class ring showing a third embodiment of my new design;

FIG. 14 is a top plan view of the ring of FIG. 13;

FIG. 15 is a bottom plan view of the class ring of FIG. 13;

FIG. 16 is a right side elevational view of the class ring of FIG. 13; a left side elevational view would be a mirror image of FIG. 16;

FIG. 17 is a front elevational view of the ring of FIG. 13; a rear elevational view would be a mirror image of FIG. 17.
